P. E. JOHNSON

BASE FOR THERAPEUTIC LAMPS

Filed Aug. 15, 1927

Inventor:
Paul E. Johnson

By
Rector, Hibben, Davis & Macauley
Atty's:

UNITED STATES PATENT OFFICE.

PAUL E. JOHNSON, OF CHICAGO, ILLINOIS, ASSIGNOR TO PAUL E. JOHNSON, INC., OF CHICAGO, ILLINOIS, A CORPORATION OF ILLINOIS.

DESIGN FOR A BASE FOR THERAPEUTIC LAMPS.

Application filed August 15, 1927. Serial No. 23,100. Term of patent 14 years.

To all whom it may concern:

Be it known that I, PAUL E. JOHNSON, a citizen of the United States, residing at Chicago, in the county of Cook and State of Illinois, have invented a new, original, and ornamental Design for a Base for Therapeutic Lamps, of which the following is a specification, reference being had to the

accompanying drawing, forming a part hereof, wherein the figure is a perspective view of a base for a therapeutic lamp embodying my new design.

I claim:

The ornamental design for a base for therapeutic lamps as shown.

PAUL E. JOHNSON.
